UNITED STATES PATENT OFFICE.

DANIEL S. COOKE, OF PROVIDENCE, RHODE ISLAND.

DRAWING-SLATE ATTACHMENT.

SPECIFICATION forming part of Letters Patent No. 253,514, dated February 14, 1882.
Application filed November 2, 1881. (No model.)

To all whom it may concern:

Be it known that I, DANIEL S. COOKE, of Providence, in the State of Rhode Island, have invented a new and useful Drawing-Slate Attachment; and I do hereby declare that the following specification, taken in connection with the drawing making a part of the same, is a full, clear, and exact description.

The object of my invention is to produce a slate, eraser, and ruler combined and attached together in such a manner that neither can become separated from the others and lost; and it consists in the device hereinafter described.

The drawing shows my invention, in which A is the slate, B the frame, and C a combined rule and eraser. D D are elastic or rubber bands, which attach the rule and eraser C to the slate-frame B, and are fastened by means of suitable eyes to the ends of the one and the sides 20 of the other, or by any other desired means. In each end of the frame is a groove, E, for receiving and retaining the ruler and eraser when not in use.

The ruler and eraser C is made in the form 25 of an ordinary wooden ruler, graduated at one edge upon one or both sides, as desired, while to the other edge there is attached, by inserting in a groove or otherwise, a strip of chamois-skin, felt, or any soft or pliable substance. At 30 each end of the ruler and eraser C is an eye, through which passes an elastic or rubber band,

which also passes through a similar eye upon each side of the slate-frame and attaches the two together, the elasticity of the connecting-bands permitting the eraser and ruler to be 35 carried to any part of the slate-surface by the hand.

When not in use the eraser and ruler C may be carried to either end of the slate and the edge thereof inserted in the groove E, as indicated by dotted lines, where it will be retained by the resistance of the bands D D until again removed by the hand.

It will now be readily seen that upon the removal of the ruler and eraser C from the groove 45 E pencil-marks may be easily removed from or lines drawn upon any part of the slate upon either side.

Either a ruler or eraser may be attached separately in the same way, if the other is not 50 required.

What I claim as my invention, and desire to secure by Letters Patent, is—

The slate A, with its grooved frame B, in combination with the ruler and eraser C and 55 elastic bands D D, the whole combined, constructed, and arranged substantially as described.

DANIEL S. COOKE.
